Filed Sept. 29, 1967, Ser. No. 8,788

Term of patent 14 years

(Cl. D37—1)

FIG. 1

FIG. 2

FIG. 3

FIGURE 1 is a front perspective view showing one end and two sides of the hollow five-sided file showing our new design;

FIGURE 2 is a front perspective view of one end and two sides showing the file of FIGURE 1 in inverted position; and

FIGURE 3 is an enlarged cross-sectional view thereof.

The incomplete showing of the external surfaces of the hollow five-sided file is understood to be representative of a conventional abrasive surface and continuous therewith.

We claim:

The ornamental design for a hollow five-sided file, substantially as shown and described.
